UNITED STATES PATENT OFFICE

2,342,190

PRINTING MACHINE

Walter T. Gollwitzer, Euclid, Ohio, assignor to
Addressograph-Multigraph Corporation, Wil-
mington, Del., a corporation of Delaware

Application October 27, 1941, Serial No. 416,636

7 Claims. (Cl. 271—11)

This invention relates to printing machines and particularly to sheet separating and feeding devices for such machines.

In my United States Patent No. 2,002,773, patented May 28, 1935, I disclose a pneumatically operated device for separating sheets from a stack in which they are arranged and for successively feeding such sheets into a printing machine, and the present invention pertains to improvements upon the device disclosed in that patent.

A primary object of the invention is to prevent, by novel means and in a novel manner, the feeding of more than one sheet at a time to the machine with which the device is used, which may be a printing or other like machine.

More specifically, it is an object of the invention to insure proper separation of the sheets by a novel combination of elements functioning in a more efficient manner and to accomplish a better result than any of the prior art sheet separating and sheet feeding devices with which I am familiar, for the purposes and use for which the new sheet separating and sheet feeding device is intended.

Another object of the invention is to detect, by novel means and in an effective manner, the inadvertent feeding of more than one sheet at a time and to prevent the passage of such plurality of sheets to a machine with which the new sheet feeder may be used.

A further object of the invention is to so arrange the sheet separating device that it may be electrically controlled from the machine with which it is used, and an ancillary object is to utilize an electromagnetically operated one-revolution clutch for effecting operating cycles of the sheet separating device.

Still another object of the invention is to provide a novel sheet separating and sheet feeding device of simple and economical construction and which is dependable in operation.

An additional object of the invention is to afford a new and improved sheet separating and sheet feeding device which is especially adapted for use with the printing machine forming the subject matter of my copending application, Serial No. 416,745, filed October 17, 1941. In such a printing machine the sheets may be advanced in a particular direction through successive printing stations to have various impressions made thereon, and may then be retracted in the reverse direction to enable still other impressions to be made thereon. It is essential that the

simultaneous feeding of a plurality of sheets be prevented in such an instance inasmuch as the plurality of sheets may become separated in the course of being advanced and retracted as aforesaid, causing the several impressions which should be made on a single sheet to be distributed over two or more separate sheets. The present invention is therefore particularly designed to feed only a single sheet at a time to the printing machine.

Other and further objects of the present invention will be apparent from the following description and claims and will be understood by reference to the accompanying drawings which, by way of illustration, show a preferred embodiment and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claims.

25 In the drawings,

Fig. 1 is an elevational view of the sheet separating and feeding device or unit, certain parts being omitted from this view for the sake of clarity;

30 Fig. 2 is a vertical sectional view taken on the line 2—2 on Fig. 1 and looking in the direction of the arrows;

Fig. 3 is a detail elevational view of a clamping collar shown in Fig. 2;

35 Fig. 4 is an elevational view looking in from the left in Fig. 1;

Figs. 5 and 6 are fragmentary elevational views looking in a direction the reverse of that in which Fig. 1 is viewed (or from the right as viewed in Fig. 2);

Fig. 7 is a detail elevational view of a rocker shown in Fig. 2;

Fig. 8 is a detail plan view of a part of a clutch shown in Figs. 1 and 4;

Fig. 9 is a schematic elevational view of the clutch structure;

Fig. 10 is a vertical sectional view taken on the line 10—10 on Fig. 6 and looking in the direction 50 of the arrows; and

Fig. 11 is an elevational view looking in from the right in Fig. 1.

This invention is related to printing machines and more especially to sheet feeding mechanisms for use therewith, the present mechanism being

particularly adapted for use with the printing machine disclosed in my copending application Serial No. 416,745, filed October 17, 1941.

When used in conjunction with such a machine, the sheet feeding unit is carried by a pair of side plates 10 and 11, Figs. 1 and 2, which are tied together by rods 12, and the entire unit is mounted in cooperative relation with the table 13 of the printing machine. The unit is supported primarily by a brace 14 which is mounted at its upper end upon one of the tie rods 12 located near the lower edges of the side plates 10 and 11, this brace being secured at its lower end to a bar 15 which forms part of the framework of the printing machine with which the new sheet-separating and sheet-feeding device is used. The lower end of the brace 14 is notched to seat on the bar 15 and is clamped to this bar by a clamping screw 17 which is threaded through a tapped opening in the brace 14 and which has a collar 16, Figs. 2 and 3, engaging the face of the bar 15 opposite the face of this bar against which the brace 14 abuts. Nuts 18 on the screw 17 serve to hold this screw locked in an adjusted position. The screw 17 has an upturned end portion serving as a crank whereby the screw and collar 16 may be rotated to clamp or release the brace 14 as the case may be, a flat 19 being provided on the collar 16 to enable withdrawal of the brace 14 from the bar 15 when the screw 17 is turned to its release position.

For the purpose of accurately locating the sheet feeding unit relative to the table 13 of the machine, blocks 20, Figs. 2 and 4, are secured to the side plates 10 and 11 and carry downwardly extending pins 21' which seat in sockets formed in a rail 22' on the frame of the printing machine. When the sheet feeding unit is thus assembled relative to the printing machine, an idler gear 21, Figs. 1, 4 and 11, rotatably mounted on a stub shaft 22 secured to the side plate 10 is meshed with a driving gear 23, Fig. 4, which is fast to a drive shaft 24 embodied in the main portion of the printing machine. The idler gear 21 serves to transmit power from the driving gear 23 to a shaft 26 that extends between and is journaled in the side plates 10 and 11. The shaft 26 carries a gear 25 outwardly of the side plate 11, and this gear 25 is meshed with a gear 27 that is rotatably mounted on a shaft 28 extending between and journaled in the side plates 10 and 11.

The shaft 26 is constantly driven rotatively so long as the idler gear 21 is meshed with the driving gear 23, but the shaft 28 is intermittently driven by the gear 27 through the medium of a clutch mechanism generally designated 29, Figs. 1 and 4. This clutch is of the type disclosed in my copending application Serial No. 239,561, filed November 8, 1938, now Patent No. 2,265,133, patented December 9, 1941, and is adapted to afford driving connection between the gear 27 and the shaft 28 during one complete revolution of the gear 27, such rotation of the shaft 28 constituting a cycle of the sheet feeding unit. Briefly, this clutch 29 has a driving member in the form of a collar 30, Fig. 1, which is secured to the hub of the gear 27, and a driven member or collar 31 which is slidably but non-rotatably mounted on the shaft 28 adjacent the collar 30. Springs 32 interposed between the driven collar 31 and another collar 33 pinned to the shaft 28 tend to urge complementary teeth on the collars 30 and 31 into engagement with each other. However, such engagement of these teeth is nor-

mally prevented by a cam plate 34, Figs. 4, 8 and 9, pivotally mounted at one end thereof on a stub shaft 35 extending outwardly from the side plate 11, this cam plate being spring-urged into engagement with the lowermost edge of the driven collar 31. As shown in the detail view, Fig. 8, the plate 34 has a cam edge 36 terminating in a recess 37 formed in a shoulder near the free end of the plate 34, which cam surface 36 cooperates with a pin 38 fixed in the collar 31 to effect disengagement of the clutch members as will be described presently, the pin 38 normally being seated in the recess 37. A roller 39 mounted on the cam plate 34 rides on the face of the gear 27, Fig. 1, to prevent lateral movement of the plate 34.

Operation of the clutch 29 is effected by a solenoid 43, Figs. 1 and 4, supported on a bracket 44 secured to the outer face of the side plate 11. A vertically extending arm 45 is pivotally connected at its lower end to the core 46 of the solenoid 43 and is urged by a spring 47 against the collars 30 and 31 adjacent the free end of the cam plate 34. A lug 48, Fig. 9, on the vertical arm 45 is disposed above the end of the cam plate 34 so that when the solenoid 43 is energized the arm 45 is retracted downwardly and the lug 48 engages and pivots the plate 34 into its broken-line position out of engagement with the pin 38 on the collar 31. Thereupon the springs 32 urge the collar 31 axially along the shaft 28 into mesh with the collar 30, Fig. 1, and the shaft 28 commences to rotate with the gear 27. As the collar 31 is driven rotatively, the pin 38 thereon strikes the arm 45 and pivots this arm to disengage the lug 48 from the end of the cam plate 34, as indicated in broken lines in Fig. 9, causing this plate 34 to be restored into engagement with the periphery of the collar 31 even though the solenoid 43 may remain energized. As the shaft 28 approaches the end of a complete revolution, the pin 38 on the collar 31 rides along the cam surface 36 on the plate 34, Fig. 8, causing the collar 31 to become disengaged from the collar 30. The pin 38 then seats in the recess 37, bringing the shaft 28 to a stop at the completion of exactly 360°. To insure seating of the pin 38 in the recess 37, a spring-urged cam follower 49a, Fig. 4, pivotally mounted on the stub shaft 35 cooperates with a cam 49 on the shaft 28, this cam having a sharp drop in which the follower 49a seats at the end of the cycle.

A sheet receptacle or rack 50, Fig. 2, is attached in a suitable manner to the sheet feeding unit and contains a supply of sheets which in the present instance may constitute check forms. The pack is supported upright at a slight angle to the vertical and the upper edges of the sheets extend above the rack 50. A suction feeding device withdraws the sheets consecutively from the rack 50 and introduces them to a sheet advancing means to be described hereinafter. This suction device comprises a sucker bar 51 which is rockably mounted in a suitable manner on the side plates 10 and 11, this sucker bar extending transversely of the machine in juxtaposition to the upper end of the rack 50. The sucker bar 51 is hollow and communicates with an exhaust duct leading to a suction pump or the like (not shown). A plurality of nozzles 52, Figs. 2 and 6, are arranged in spaced relation on the sucker bar and are movable to and from engagement with the pack of sheets.

For the purpose of imparting rocking movement to the sucker bar 51, an L-shaped lever 53,

Figs. 2 and 5, is pivotally connected at one end thereof to a depending portion of the sucker bar 51 and at its other end is pivoted to a shaft 81 journaled in the side plates 10 and 11, the two arms of the lever 53 being pivotally interconnected at the bend of this lever by a pin 53'. A roller 55 rotatably mounted on the pin 53' cooperates with a cam 56 fast on the aforesaid shaft 28, a spring 57 acting on one arm of the lever 53 to urge the roller 55 against the periphery of the cam 56. The cam 56 is generally of circular configuration and is provided with a drop and an adjoining dwell. When the lever 53 is in its normal position shown in Fig. 2, which position it assumes when the roller 55 is riding on the circular portion of the cam 56, the sucker bar 51 is then in its lowermost position. This sucker bar has a valve 60 provided with an operating arm 61 which cooperates with a pin 62 stationarily mounted on the tie rod 12 to which the brace 14 is pivoted. The arm 61 engages the pin 62 whenever the sucker bar 51 assumes the lowermost position just referred to, and thereupon opens the valve 60 to destroy the suction in the nozzles 52.

When in the course of a cycle of operation of the sheet feeding unit the drop in the cam 56 moves opposite the roller 55, the spring 57 thereupon rocks the lever 53 clockwise (as viewed in Fig. 2) to raise the arm 61 of the valve 60 out of engagement with the stationary pin 62, thereby restoring the suction in the nozzles 52, and to bring these nozzles 52 into engagement with the foremost sheet in the pack. The roller 55 then rides up on the dwell of the cam 56, causing the sucker bar 51 to commence its return movement effecting withdrawal of a sheet from a rack 50.

When a sheet is withdrawn from the pack by the sucker bar, it is presented to a sheet advancing means which feeds the sheet toward suitable conveying means on the table 13 of the printing machine. Such sheet advancing means includes feed rollers 65, Figs. 1 and 2, which are mounted on the shaft 26 in spaced relation and are individually secured thereto by set screws 66. As the roller 55 rides onto the circular periphery of the cam 56, Fig. 2, the nozzles 52 are moved so as to pass below the periphery of the feed rollers 65 and the valve 60 is opened in the manner explained hereinabove to relieve the suction in the nozzles. Shortly prior to the time the suction is destroyed, however, the leading edge of the sheet is clamped against the feed rollers 65 by clamping rollers 67 and the sheet is frictionally advanced by the rollers 65 and 67 toward the table 13 of the printing machine. Preferably the central clamping roller 67 is knurled so that it may firmly grip the sheet to prevent slippage thereof.

The clamping rollers 67 are secured to a shaft 68 which is journaled at its ends in adjustable bearings 69, Fig. 7, carried by rockers 70 that are pivotally mounted on the shaft 26 inwardly of the side plates 10 and 11, respectively. The clamping rollers 67 are thus capable of bodily movement about the shaft 26 as a center and may be retracted slightly to enable the leading edge of a sheet to be placed against the peripheries of the feed rollers 65 by the suction nozzles 52, whereupon the clamping rollers 67 may be restored to press the leading edge of the sheet against the feed rollers 65.

Such retraction and advance of the clamping rollers 67 relative to the feed rollers 65 is effected by cams 71, Figs. 1 and 2, mounted on the intermittently driven shaft 28, which cams cooperate

with rollers 72 rotatably mounted on the rockers 70. Springs 73 are extended between anchors in the side plates 10 and 11 and the rockers 70 to urge the followers 72 into engagement with the peripheries of the cams 71, and as these cams are rotated the followers 72 drop into recesses in the cams 71 and the clamping rollers 67 are shifted into sheet engaging position. When the followers 72 ride onto the rises of the cams 71, the clamping rollers 67 are retracted out of such sheet engaging position, this occurring just before a new sheet is to be introduced into the bite of the feed rollers.

As shown in Fig. 7, the bearings 69 for the shaft 68 are positioned in recesses in the rockers 70 and are movable therein toward and away from the shaft 26. A screw 74 extends upwardly from each bearing 69 through an opening in a strip 75 which bridges the aforesaid recess and is secured to the rocker 70. A small compression spring 76 interposed between each bearing 69 and strip 75 tends to urge the shaft 68 radially toward the shaft 26. A nut 77 is threaded on each screw 74 and is provided with teeth that cooperate with teeth cut into the strip 75 to afford a detent for adjusting the pressure with which the sheets are gripped by the clamping rollers 67.

Preferably the clamping rollers 67 are positively driven, and to this end a gear 78, Fig. 1, on the shaft 68 is meshed with a gear 79 on the shaft 26, the ratio of these gears being such that the clamping rollers 67 and feed rollers 65 are driven at substantially the same peripheral speed. It will be understood that sufficient clearance exists between these gear teeth to enable proper adjustment of the clamping rollers in the manner just described.

It is desirable that not more than one sheet at a time shall be fed between the rollers 65 and 67, and hence several devices are provided in the present instance to insure separation of the sheets individually from the pack. One such means comprises fingers 80, Figs. 1 and 2, which are individually secured to the shaft 81 and are adapted to move into engagement with the sheets in the rack 50 to retain the sheets therein as the foremost sheet is being withdrawn by the nozzles 52, as many of these retaining fingers 80 being provided on the shaft 81 as may be necessary to perform this function. Rocking movement is imparted to the shaft 81 by a cam 82, Fig. 11, on the shaft 28, which cam engages a follower 83 on a spring-urged rocker arm 84 on the shaft 81, whereby the fingers 80 are reciprocated in timed relation with the withdrawal of sheets from the pack.

To further insure that the sheets are properly separated, air ducts 85, Figs. 1, 2, 5 and 6, are disposed adjacent the side edges of the pack of sheets to direct blasts of air from both sides of the pack against the edges of the sheets, thereby ruffling the sheets and facilitating separation of the foremost sheet from the pack. The ducts 85 are clamped to a rod 86 carried by the side plates 10 and 11 and are connected by flexible hosing 87, Fig. 1, to a pipe 88 supported on the side plate 11, this pipe communicating with a source of compressed air (not shown).

Still another device which aids to prevent feeding of more than one sheet at a time from the rack 50 is the stripper 90, Figs. 2 and 6, which is adjustably supported on the end of a lever arm 91 by means of a screw-and-slot connection. The arm 91 is pivotally mounted on a tie rod 12 near the top of the unit and is connected by a pin

92 and an eccentric screw 93 to an arm 94 carrying a roller 95 which rides on the periphery of a cam 96 on the shaft 26. A leaf spring 97 fastened to the tie rod 12 bears against the head of the eccentric screw 93 to urge the roller 95 against the cam 96. As this cam is rotated the stripper 90 is lowered and raised in timed relation with the withdrawal of sheets from the rack 50. The lower edge of the stripper plate 90 is serrated as indicated at 99, Fig. 2, so that when the stripper 90 is lowered, the serrated edge 99 is effective to comb out the sheets and thereby facilitate separation thereof. A pin 98 extending radially from the eccentric screw 93 enables this screw to be turned for accurately adjusting the relative angularity of the arms 91 and 94.

There may be occasions when two or more sheets are simultaneously advanced by the sucker nozzles 52 into the bite of the rollers 65 and 67, despite the action of the aforesaid sheet separation devices, and because of this I provide a safety device which responds under such circumstances to prevent the feeding of the sheets to the printing machine. As shown in Figs. 6 and 10, a disc 100 (not shown in Figs. 1 and 2) is rotatably mounted on the shaft 26 adjacent a feed roller 65 but out of alignment with the associated clamping roller 67. A rod 101, Figs. 1, 7 and 10, extends between and is carried by the rockers 70 which carry the shaft 68 on which the clamping rollers 67 are mounted. A bracket 102, Figs. 6 and 10, is secured to this rod 101, and adjacent this bracket a caliper shoe 103 is pivotally mounted on the rod 101 in alignment with the disc 100. The shoe 103 has an upwardly extending arm 104 which is connected by a spring 105 to the bracket 102. The spring 105 urges the arm 104 into engagement with the end of an adjusting screw 106 mounted in the bracket 102, whereby the separation of the shoe 103 and disc 100 may be accurately determined. The shoe 103 is so adjusted that a sufficient clearance is provided between it and the disc 100 to permit passage of a single sheet without any tendency to rotate the disc 100. However, if two or more sheets attempt to pass between the shoe 103 and the disc 100, there is a binding effect and the disc 100 is rocked clockwise away from its normal position shown in Fig. 10, the shoe 103 being unable to yield because of the engagement of its arm 104 with the end of the screw 106.

An arm 107 attached to the disc 100 carries an arm 108 which cooperates with a normally open switch 109 mounted on one of the lower tie rods 12. The contact springs of this switch normally urge the arm 108 in a direction to maintain the arm 107 in engagement with the tie rod 12. However, when a double feed occurs to cause the disc 100 to rotate, the arms 107 and 108 are shifted to bring about closure of the switch contacts 109, and thereupon a warning signal is given or a control operation may be effected such as by suspending operation of the sheet feeding unit or diverting the double out of the normal path of movement of the sheets.

There may be instances in which a sheet feeding unit is employed in conjunction with a printing machine which is set up for multiplicate printing operations, that is, where each sheet receives more than one impression from the printing means of the machine. In such case it is, of course, desired that the sheets be fed at intervals which are farther apart than the interval in which a single impression is made on each such sheet. The sheet feed may be properly timed in

this respect by energizing the solenoid 43 under control of a timing switch in the main part of the machine, as explained in my aforesaid co-pending application Serial No. 416,745.

5 From the foregoing it is apparent that I have provided a dependable apparatus for separating and feeding sheets and which embodies several advantageous features. Thus, for instance, the provision of the electrically controlled, one-revolution clutch drive affords a flexible arrangement in which the cycles of operation of the sheet feeding unit may be selectively timed with relation to the operation of the printing machine. Moreover, it is not necessary that the idler gear 10 21 carried by the sheet feeding unit, and the driving gear 24 in the printing machine, occupy any particular rotative positions relative to each other when meshed. Other important features consist in the provision of the air blast ducts 85, 15 the sheet retaining fingers 80 and the stripper 90, these elements in combination serving to insure proper separation of the sheets. The positive drive of the clamping rollers 67 and the knurled configuration of the central clamping roller 67 serve to minimize the possibility of slippage or damaging of the sheets. In the event 20 a double feed occurs despite the action of the aforesaid sheet separating devices, the detecting means including the caliper shoe 103, disc 100 and switch 109 then functions to furnish a warning indication or to effect an appropriate control 25 operation.

While I have illustrated and described a selected embodiment of my invention, it is to be understood that this is capable of variation and modification and I therefore do not wish to be limited to the precise details set forth but desire to avail myself of such changes and alterations as fall within the purview of the following 30 claims.

I claim:

1. In a device for separating and feeding sheets consecutively from a stack thereof disposed in said device, a feed roller, suction nozzles, means 45 for moving said suction nozzles into engagement with the forwardmost sheet in the stack and for then moving said nozzles past the periphery of said feed roller to engage the sheet with said feed roller, a clamping roller, means for retracting said clamping roller along the periphery of the feed roller to enable engagement of the sheet with said feed roller and for advancing said clamping roller along the periphery of the feed roller into position to clamp the sheet in engagement with said feed roller, a stripping member movable into engagement with the leading edges of the sheets in said stack and having a serrated edge for combing out said sheets and thereby 50 facilitating separation of the forwardmost sheet from the stack by said nozzles, and means moving said stripping member to and from engagement with the stack in timed relation with the movement of said nozzles.

2. In a device for separating and feeding sheets 55 consecutively from a stack thereof disposed in said device, a feed roller, suction nozzles, means for moving said suction nozzles into engagement with the forwardmost sheet in the stack and for then moving said nozzles past the periphery of said feed roller to engage the sheet with said feed roller, a clamping roller, means for retracting said clamping roller to enable engagement of the sheet with said feed roller and for advancing said clamping roller into position to 60 clamp the sheet in engagement with said feed roller.

70 75

roller, and means for caliper said sheets as they are fed between said feed and clamping rollers to thereby detect the passage of more than a single sheet at a time, said caliper means comprising an element rockably mounted coaxially of said feed roller in the path of travel of said sheets, a shoe positioned in alignment with said element, said element and said shoe having opposed arcuate surfaces between which the sheets pass, means for adjusting the clearance between said shoe and element whereby the passage of more than a single sheet at a time causes said element to be rocked, and means responding to such rocking movement of said element in a manner indicative of an abnormal condition in the feeding of the sheets.

3. In a device for separating and feeding sheets consecutively from a stack thereof disposed in said device, a drive shaft, a feed roller mounted on said drive shaft, suction nozzles, means for moving said suction nozzles into engagement with the forwardmost sheet in the stack and for then moving said nozzles past the periphery of said feed roller to engage the sheet with said feed roller, a clamping roller opposed to said feed roller, means for retracting said clamping roller along the periphery of the feed roller to enable engagement of said forwardmost sheet with said feed roller and for advancing said clamping roller along the periphery of the feed roller into position to clamp the sheet in engagement with said feed roller, means for relieving the suction in said nozzles subsequent to movement thereof past the periphery of said feed roller and subsequent to advancing of said clamping roller, and means interconnecting said clamping roller and said drive shaft for positively driving said clamping roller at substantially the same peripheral speed as said feed roller.

4. In a device for separating and feeding sheets consecutively from a stack thereof disposed in said device, a feed roller, suction nozzles, means for moving said suction nozzles into engagement with the forwardmost sheet in the stack and for then moving said nozzles past the periphery of said feed roller to engage the sheet with said feed roller, a clamping roller opposed to said feed roller, means for retracting said clamping roller to enable engagement of said forwardmost sheet with said feed roller and for advancing said clamping roller into position to clamp the sheet in engagement with said feed roller, means for directing a blast of air against the edges of the sheet in the stack to thereby ruffle out the sheets when said nozzles are advanced into engagement with the forwardmost sheet, a stripping member movable into engagement with the leading edges of the sheets in said stack and having a serrated edge for combing out said sheets and thereby facilitating separation of the forwardmost sheet from the stack by said nozzles, and means mov-

ing said stripper member to and from engagement with the stack in timed relation with the movement of said nozzles.

5. A device as set forth in claim 4, including a finger reciprocated in timed relation with the movement of said nozzles and engaging said stack to assist said stripping member in restraining movement of unwanted sheets from the stack.

6. In a device for separating and feeding sheets consecutively from a stack thereof disposed in said device, a drive shaft, a feed roller fast on said drive shaft, a member pivotally mounted on said drive shaft, a shaft journaled in said member and extending parallel to said drive shaft, a clamping roller fixed to the second-named shaft in opposed relation to said feed roller, a cam shaft, means affording a driving connection between said drive shaft and said cam shaft, suction nozzles, a cam on said cam shaft for effecting movement of said nozzles into engagement with the forwardmost sheet in the stack and for then moving said nozzles past the periphery of said feed roller to engage the sheet with said feed roller, another cam on said cam shaft for rocking said pivoted member to thereby effect retraction of said clamping roller circumferentially of said feed roller to enable said forwardmost sheet to engage said feed roller and for then advancing said clamping roller into position to clamp said sheet against said feed roller, and intermeshing gears on said drive shaft and said clamping roller shaft for positively driving said clamping roller at substantially the same peripheral speed as said feed roller.

7. In a device for separating and feeding sheets consecutively from a stack thereof disposed in said device, a drive shaft, a feed roller fast on said drive shaft, a member pivotally mounted on said drive shaft, a shaft journaled in said member and

extending parallel to said drive shaft, a clamping roller fixed to the second-named shaft in opposed relation to said feed roller, a cam shaft, means affording a driving connection between said drive shaft and said cam shaft and includ-

ing a clutch operable when actuated to effect a cycle of rotation of said cam shaft, an electromagnet for intermittently actuating said clutch, suction nozzles, a cam on said cam shaft for effecting movement of said nozzles into engagement with the forwardmost sheet in the stack and for then moving said nozzles past the periphery of said feed roller to engage the sheet with said feed roller, and another cam on said cam shaft for rocking said pivoted member to thereby effect retraction of said clamping roller circumferentially of said feed roller to enable said forwardmost sheet to engage said feed roller and for then advancing said clamping roller into position to clamp such sheet against said feed roller.

WALTER T. GOLLWITZER.
